CLAIM

I claim the ornamental design for a multi-purpose wood-working accessory, as shown and described.

DESCRIPTION

FIG. 1 is a front elevational view of a multi-purpose woodworking accessory showing my new design therefor; FIG. 2 is a rear elevational view; FIG. 3 is a top plan view; FIG. 4 is a right side elevational view, the left side elevational view being a mirror image thereof; and, FIG. 5 is a bottom plan view.
